BRIDLE BIT

Pascal M. Kelly, El Paso, Tex., assignor to P. M. Kelly & Sons, Manufacturers, El Paso, Tex., a company of Texas

Filed May 29, 1961, Ser. No. 65,375

Term of patent 14 years

(Cl. D38—2)

The FIGURE is a perspective view of a bridle bit showing my new design.

The essential features of my design reside in the shape and arrangement of the nose band, head stall ring and intermediate portion and the positioning of this combination of units with respect to the curb strap ring and rein rings.

I claim:

The ornamental design for a bridle bit, substantially as shown and described.
